ABSTRACT: A cigarette lighter assembly mounted on an accessible wall of a household stove and including, a hand removable and insertable cigarette lighter in a lighter socket and an electrically insulated mounting plate for mounting the lighter assembly to the accessible wall. The lighter being removable from the socket through the concentric openings in the accessible wall and the mounting plate.

CIGARETTE LIGHTER ASSEMBLY

BACKGROUND OF THE INVENTION

This invention broadly relates to a cigarette lighter assembly for use in combination with the control panel of a household stove. In the past, common household stoves of the gas or electric variety have normally been provided with, for example, four burners mounted on the top portion of the stove. As is known, people in the household having such a stove often use it for lighting cigarettes, cigars or the like, when common matches or other cigarette lighters are either not available or inconvenient to reach at the precise moment it is desired to indulge in the smoking habit. In such a situation smokers have often been prone to use one of the burners of the stove for lighting the cigarette, and such a use of the stove burner is, of course, extremely dangerous in that in order to light the cigarette, cigar, etc. with the stove burner, it is necessary to bend over and place the face very close to the burner during the cigarette lighting. As a result, singed eyebrows, burnt hair and the like often result from using the conventional stove burner to light a cigarette. In the invention disclosed hereinbelow this problem is overcome in that the development has been made to the effect that a cigarette lighter of the type extremely popular in automobiles has been uniquely adapted for use on the control panel of a stove to make use of the normal electric current which is provided to the chassis of the stove such that the cigarette lighter mounted on the stove control panel can be used to light a cigarette at any time, without the need to make use of the dangerous habit of bending over to light the cigarette from a stove burner when other lighting techniques such as matches, pocket lighters, etc. are not available.

Accordingly, it is the object of this invention to provide in combination with a household stove a cigarette lighter assembly mounted on the control panel of said stove.

Other objects, features and advantages of the present invention will become apparent from the subsequent description and the appended claims taken in conjunction with the accompanying drawings.

BRIEF DESCRIPTION OF THE DRAWINGS

FIG. 1 illustrates a conventional household stove modified in accordance with this invention; and

FIG. 2 illustrates a cross-sectional view taken along the line of 2-2 of FIG. 1 showing the particulars of the cigarette lighter assembly as mounted on the panel of the stove of FIG. 1.

SUMMARY OF THE INVENTION

Briefly stated, this invention involves in combination with a household stove apparatus comprised of a base, a front panel, side panels, a plurality of stove burners, and generally top-mounted control panel means for utilizing one or more of the burners in a cooking operation, the improvement comprising a cigarette lighter assembly mounted generally proximate said control panel means and including a hand removable and insertable cigarette lighter, a spring which normally biases said lighter out of contact with a thermal contact heating means for heating the lighter to an approximate predetermined temperature at which the lighter disengages and is ready for operative use, insulated electrical connector means for resistance heating said thermal contact means, said connector means being operatively associated with an electrical power source wire means mounted within the stove for appropriately providing electric current to the thermal contact means when the lighter is pressed into engagement therewith.

DESCRIPTION OF PREFERRED EMBODIMENTS

FIGS. 1 and 2 of the drawings show a household stove which has incorporated therein a cigarette lighter assembly as indicated by the cross-sectional or cutaway view in FIG. 2. The stove is generally designated 10 and is comprised of side panels 12, front panel 14, and a top deck or table portion 16 in

which there are mounted several burners designated 18. The stove also includes a control panel 19 which has mounted or constructed into the right end portion thereof a cigarette lighter assembly designated 20.

5 The cigarette lighter assembly 20 is comprised of a lighter 22 which is removable or insertable into the lighter socket 24. The lighter 22 has concentrically and axially arranged thereabout a spring 26 which normally biases the lighter such that it remains out of contact with a thermal contact heating means 28. The thermal contact heating means 28 is electrically connected with a terminal post 30 which has at one end thereof a threaded nut 32 which may satisfactorily be used to connect a lead wire 34 to the terminal post 30. The post 30 is insulated by the insulation material designated 36. The insulation 36 acts to insulate the electrical post 30 from the socket housing 24. A second terminal means designated 40 is mounted on the exterior of the socket housing 24 and shown attached thereto is another electrical wire 42.

20 The electrical conductors 34 and 42 are suitably connected

through a transformer means (not shown) to a 110volt power

supply, which is comprised of two wires (not shown) introduced through the electrical conduit 50. The electrical

25 conduit 50, as shown, is mounted generally adjacent to the

lighter assembly through the use of the housing means 52, but

it should be understood that the housing means 52 is not

necessary to the practice of the invention.

The housing 52 in turn is mounted to the front control panel

19 through means of screws 54 and nuts 56. The front plate 60

30 for mounting the lighter assembly to the control panel 19 is

held in position by the screws 62 and nuts 64.

To operate the cigarette lighter 22 it is pushed in until the

55 spring 26 is completely depressed, and this in turn brings the

sleeve portion 27 into firm electrical contact with the metal

socket housing 24. This contact between the metal sleeve 27

and the socket housing 24 completes the electrical circuit for

heating the lighter. The lighter itself is comprised of a wound

resistance heater element positioned within the holder

40 member 29. The holder member 29 when the lighter 22 is

pressed into engagement is positioned within the elastically

engageable receiver 31 and thus elastically engageable receiver

31 and this elastically engageable receiver 31 in turn

50 holds the lighter in depressed position while the thermal

contact heating means 28 heats the wound resistance heater

within the member 29 to an essentially red hot temperature.

Once the hot temperature is reached, then the thermal expan-

55 sion causes the elastically engageable receiver to expand and

release the member 29 whereby the biased spring 26 pops the

lighter out a relatively small amount and this popping out ac-

50 tion is observed by the user and then the lighter 22 is grasped

by the hand and removed from the socket housing 24 for use

in lighting a cigarette, cigar, etc.

While it will be apparent that the preferred embodiments of

55 the invention disclosed are well calculated to fulfill the objects

above stated, it will be appreciated that the invention is

susceptible to modification, variation and change without de-

parture from the proper scope or fair meaning of the sub-

joined claims.

60 I claim:

1. A cigarette lighter assembly mounted on an accessible

wall of a household stove and including, a hand removable

and insertable cigarette lighter in a lighter socket a concentrically axially arranged spring which normally biases said lighter

65 out of contact with a thermal contact-heating means for heating

the lighter to an approximate predetermined temperature

70 at which the lighter disengages from heating contact with an elastically engageable receiver on the heating means, and is

ready for operative use, insulated electrical connector means

75 comprised of two conductor wires for resistance heating said

thermal contact means, said connector means being opera-

tively connected to an electrical power source for ap-

propriately providing electric current to the thermal contact

means when the lighter is pressed into engagement therewith,

an electrical conduit means for holding said conductor wires,

housing means generally surrounding said lighter assembly, second connector means for connecting the housing means to the accessible wall of the stove, electrically insulated front mounting plate means for mounting the lighter assembly to the

accessible wall, and third connector means for connecting the front mounting means to the accessible wall, said lighter being removable from said socket through the concentric openings in said accessible wall and mounting plate means.
